SLUSH PUMP CYLINDER CLOSING MEANS
Raymond A. Pangburn, P.O. Box 94364,
Oklahoma City, Okla. 73109
Filed Aug. 22, 1966, Ser. No. 573,967
2 Claims. (Cl. 103—216)

The present invention is a continuation-in-part of my copending applications Ser. No. 420,082, filed Dec. 21, 1964, now Patent No. 3,277,837 for Pump Cylinder Closing Means, and Ser. No. 437,125, filed Mar. 4, 1965, for Slush Pump Valve Pot Cover.

This invention is an improvement over the above referred to applications by providing a splined plug and lock ring cooperating with a pressure cap and an adjusting bolt for engaging a pump cylinder liner.

Slush pumps of relatively large capacity are conventional equipment in oil well drilling and are used for circulating the drilling fluid. These pumps have generally cylindrical-shaped upwardly open intake and exhaust fluid transferring bodies, commonly called valve pots which are respectively equipped with fluid intake and exhaust valves. The valve pots are in fluid communication with respective pump cyclinders, the latter each having a reciprocating piston. The slush pump cylinder is closed at the head end of the pump by bolted on head including a central threaded stud bolt engageable with a plug or head member in turn contacting a liner spool which holds the cylinder liner in place and spreads packing into sealing relation with the wall of the cylinder. The liner packing becomes compressed during operation of the pump and permits longitudinal movement of the liner spool and liner in response to the reciprocating action of the pump piston which results in excessive wear of the mating parts.

It is, therefore, the principal object of this invention to provide an improved closing means for slush pump cylinders which may be quickly and easily assembled and removed to service the pump.

Another object is to provide a cover for a pump cylinder including a single bolt and nut which is connected in a novel manner with the head end of the pump cylinder.

Yet another object is to provide a device of this class which may be connected with an existing slush pump or incorporated in the design of slush pump bodies to be manufactured with a relatively simple change thereof.

A further object is to provide a device of this class wherein tightening the bolt or nut selectively applies pressure to the cylinder liner spool or the liner.

The present invention accomplishes these and other objects by connecting cooperating splined means to the open end of a slush pump cylinder which engages and bears against the liner spool.

Other objects will be apparent from the following description when taken in conjunction with the accompanying single sheet of drawings, wherein:

FIGURE 1 is a fragmentary vertical cross-sectional view of the head end portion of a slush pump cylinder having the device installed thereon;

FIGURE 2 is an exploded perspective view of the components of the invention shown in FIG. 1; and

FIGURE 3 is a view similar to FIG. 1 illustrating an alternative embodiment.

Like characters of reference designate like parts in those figures of the drawings in which they occur.

In the drawings:

The reference numeral 10 indicates a fragment of the fluid end of a conventional slush pump having a body portion 12 and a cylinder 14 therein which receives a liner 16 in which a piston 18 is reciprocated. The body 12 is provided with an enlarged head end opening 20 coaxial

2

with respect to the cylinder 14 for receiving a liner spool 22. The body 12 is further counterbored, as at 24, which is intersected by the conventional valve pot opening 26. The liner spool 22 is provided with openings 28 to provide communication between the cylinder liner and the valve pot opening 26. The body 12 is circumferentially enlarged around the liner 16 adjacent the inward end of the liner spool to form an annular shoulder 30. The liner 16 is provided with an annular flange 32 adjacent the head end of the pump. Packing 34 is interposed between the liner flange 32 and the body shoulder 30. This packing 34 must be compressed by movement of the liner flange 32 toward the shoulder 30 to form a seal between the liner and pump body which is accomplished in the following manner.

The conventional cylinder head, not shown, is removed and replaced by a lock ring 40. The lock ring 40 is provided with a central opening 42 diametrically substantially greater than the diameter of the counterbore 20. The inner wall of the lock ring 40 is provided with an inwardly extending annular flange 44 forming a shoulder 46 in spaced relation with respect to the head end of the pump body 12. The inside diameter of the flange 44 is substantially equal with respect to the diameter of the counterbore 20. The flange 44 is provided with a series of diametrically opposite slots 48 to form a series of splines 49. Bolts and nuts 50 connect the lock ring 40 to the body 12 coaxial with respect to the cylinder opening 14. Alternatively the configuration of the lock ring 40 may be cut into the head end portion of the body 12 if sufficient body material is present.

Cylinder opening plug means 52, having a circumferential row of cooperating splines 54, intermediate its ends, freely received by the spline forming slots 48, is placed within the lock ring 40. The diameter of the plug means 52, exclusive of the splines 54, is substantially less than the diameter of the counterbore 20 for the reasons presently apparent. The spline 54 of the plug 52 are dimensioned so that they slide freely between the splines 49 of the lock ring and are freely received between the lock ring splines 49 and the adjacent end surface of the body 12 so that the plug 52 may be rotated about the longitudinal axis of the cylinder 14 to position its splines 54 in respective alignment with the splines 49 of the lock ring. The plug 52 is centrally bored and threaded, as at 56, for the purposes presently explained.

A pressure plate or cap 58, diametrically substantially equal to the counterbore 20, is provided with a plurality of spaced-apart legs or fingers 60 which are cooperatively received slidably between the aligned splines 49 and 54 of the plug and ring. The length of the fingers 60 is substantially greater than the length of the plug 52. The free ends of the fingers 60 are welded to a pressure ring 62 which surrounds the inwardly projecting end portion 55 of the plug 52 within the counterbore 20.

The adjacent end portion of the liner spool 22 is diametrically reduced to form an annular shoulder 64 which receives a packing spreader ring 66. A packing ring 68 is interposed between the spreader ring 66 and the pressure ring 62.

A threaded bolt or shaft 70 projects through the bore of the cap 58 and is threadedly engaged with the plug threads 56. The inward end of the shaft 70, when tightened, thus bears against the outwardly disposed end of the liner spool 22 thus forcing its inner end portion toward the liner 16. The inward end portion of the liner spool 22 is provided with a rabbitted edge 72 for cooperative engagement with the outwardly projecting or head end of the liner 16 for a metal to metal contact. Pressure applied to the liner spool 22 by the shaft 70 thus moves the liner 16 inwardly and compresses the pack-

ing 34 to form a seal with the body 12. A nut 73, threaded-
ly engaged with the shaft 70, is tightened against the
pressure cap 58 to force the pressure cap inwardly and
force the pressure ring 62 against the packing ring 68
which is spread by the spreader ring 66 for forming a
5 seal between the outer end portion of the liner spool 22
and the counterbore 20.

Referring more particularly to FIG. 3, identical parts
shown bear identical reference numerals. The liner 16A is
provided with an annular shoulder 32A spaced away from
the end of the liner contacting the liner spool 22A. The
liner spool 22A is diametrically substantially equal to the
10 diameter of the liner 16A and is surrounded by a sleeve
80 which contacts, at its inner end, similar packing 34A
surrounding the liner 16A adjacent the forward surface
of the annular liner flange 32A. The spreader ring 66
and packing ring 68 are interposed between the other
15 end of the sleeve 80 and the pressure ring 62. The sleeve
80 is similarly provided with slots or openings 82 which
communicate with the liner spool openings 28A. Thus
when the shaft 70 is tightened the liner spool 22A bears
against the adjacent end of the liner 16A to force its
20 ring 32A into contact with the body shoulder 30. Tightening
the nut 73 forces the pressure cap 58 and its pressure
ring 62 against the packing ring 68 in turn moving the
sleeve 80 into contact with the liner packing 34A to
25 simultaneously form a positive seal between the liner 16
and the body 12 and between the liner spool 22A and
the counterbore 20.

Operation

When installing the device on an existing slush pump
the cylinder head, not shown, is removed and the lock
ring 40 is installed in its place. The liner 16 and its
packing 34 is inserted into the cylinder. The liner spool
22 is positioned adjacent the outwardly disposed end of
the liner. The spreader ring 66 and packing ring 68 are
30 positioned on the outwardly disposed end of the liner
spool. Prior to assembly the pressure cap 58 is placed
on the plug 52 and the free ends of the pressure cap fingers
60 are welded to the pressure ring 62. This assembled unit,
35 pressure cap 58, plug 52, and pressure ring 62, are then
positioned within the lock ring 40. The plug 52 and pres-
sure cap 58 are then rotated to align the splines 54 of the
40 plug with the splines 49 of the lock ring 40. The shaft 70
is then screwed into the plug 52 and tightened against
the liner spool 22. The nut 73, normally in place on the
shaft 70, is then tightened against the pressure cap 58.
The device is removed by reversing the above described
45 installation.

50

The alternative embodiment of FIG. 3 is installed in
the identical manner with the exception that the sleeve 80
is installed prior to installation of the liner spool 22A.

It seems obvious that, when constructing new pumps,
the slotted or splined lock ring 40 may be formed integral
with the pump body.

Obviously the invention is susceptible to some change
or alteration without defeating its practicability, and I
therefore do not wish to be confined to the preferred em-
bodiment shown in the drawings and described herein,
further than I am limited by the scope of the appended
claims.

I claim:

1. In a pump having a body, a cylinder opening out-
wardly of said body, a liner in said cylinder, a liner spool
bearing against said liner, the combination of: lock ring
means secured to said body coaxial with respect to said
cylinder, said lock ring means including an inwardly pro-
jecting splined flange disposed in spaced relation with
20 respect to the outwardly open end of said cylinder, said
splined flange defining a diameter at least as great as the
diameter of said cylinder; plug means closing the open
end of said cylinder and lockably engaging said lock ring
means, said plug means being substantially cylindrical
25 and provided with a circumferential row of splines co-
operatively received by the splines in said lock ring means;
and means engaged with said plug means for moving said
liner and said liner spool toward sealing contact with
said cylinder, the last said means including a shaft ex-
tending coaxially through and threadedly connected with
30 said plug means, a pressure cap surrounding said shaft
outwardly of said plug means, said pressure cap having
a plurality of fingers projecting through the splines on
said plug means, and a nut threadedly engaged with said
shaft outwardly of said pressure cap.

2. Structure as specified in claim 1 and packing sur-
rounding the adjacent end portion of said liner and said
liner spool forming a seal between said liner and said
liner spool and the body, respectively, upon rotation of
40 said shaft and said nut, respectively.
